UNITED STATES PATENT OFFICE.

HAROLD EDGAR WHITTAKER, OF PRESTON, ENGLAND, ASSIGNOR TO THE WHITTAKER LOOM COMPANY, LIMITED, OF PRESTON, ENGLAND.

AUTOMATIC WEFT-REPLENISHING MECHANISM OF LOOMS.

Original application filed September 30, 1924, Serial No. 740,826, and in Great Britain November 27, 1922.
Divided and this application filed July 17, 1925. Serial No. 44,375.

This invention relates to automatic weft replenishing mechanism for looms of the kind comprising a swivel adapted to actuate a transerrer and having means for preventing the swivel from so actuating the transerrer in the event of the shuttle not being properly positioned in the shuttle box.

The object of the present invention is to devise improved weft replenishing mechanism of the above character, and the invention consists in automatic weft replenishing mechanism for looms of the kind referred to comprising in combination a transerrer, a swivel for actuating the transerrer, a movable member carried by the swivel and normally adapted to be positioned for moving the transerrer when the swivel is operated and means adapted to move said member so that the transerrer will be out of its path in the event of the shuttle not being properly positioned in the shuttle box.

The invention also consists in the apparatus hereinafter described.

The accompanying drawings illustrate one mode of carrying out the invention.

Figure 1 is a plan of a part of the mechanism showing the transerrer and mechanism associated therewith for actuating the same and for preventing actuation when the shuttle is not in its proper position.

Figures 2 and 3 are similar views showing the parts in different positions, and

Figure 4 is a side view of the transerrer and swivel.

In carrying my invention into effect in one convenient manner I may form my transerrer somewhat in the manner described in the specification of my copending application No. 740,826, filed Sept. 30, 1924, of which this application is a division, that is to say, of substantially L formation in plan comprising an arm k by which it is mounted on the transerrer shaft l and at the end of which is the hammer or transerrer proper k' extending across the interior of the magazine in position to engage when depressed the lowermost cop in the magazine, the hammer k' extending substantially at right angles from the arm k. The latter is provided with a shoulder or projection k² with which engages a pin m, shaft or other projection upon the swivel m' which is mounted co-axially with the hammer so that when the swivel is depressed by the action

of the feeler mechanism for weft replenishing a bunter on the sley engages a projection on the swivel, and in its forward stroke thus rotates the swivel (in the manner shown in Figure 4) causing the pin m thereon to engage with the shoulder or projection k² upon the hammer in order to rotate the latter for transfer of the cop.

In order, however, that the transfer may not be effected unless the shuttle is properly positioned in the shuttle box I arrange the pin or member m upon the swivel to be controlled by a spring n and provide means in connection therewith which will enable the spring to move the member so that the shoulder or projection k² upon the hammer arm will be out of the path of the member so that the hammer arm will not be actuated on rotation of the swivel.

In the construction illustrated this is effected by means of a detector comprising a longitudinally movable member o slidable in a bracket p secured to the breast beam and provided with an attachment o' which holds the pin m upon the swivel in place against the action of its spring n, such detector either acting direct upon the pin or projection m or indirectly through the medium of a collar q which is secured by a set screw or otherwise to the pin or projection m and which is rotatable with the swivel round the hammer shaft l. The collar q is preferably of an elongated form in one direction as compared with the other, the arrangement being such that with the swivel in its normal position shown in Figure 4 the detector attachment o' is movable in the direction of the long axis of the collar, thus rendering it free from any liability to slip off with loom vibration but when the swivel is depressed by the action of the feeler motion as shown in Figure 3 the collar q is also rotated so that the detector attachment o' retains only a very fine hold upon the collar. If, however, the shuttle r is not properly positioned the nose r' or some other part of the shuttle during the forward movement of the sley comes into contact with the end of the detector arm o thus moving the latter (if necessary against a suitable spring) and freeing its attachment o' from the collar q in the manner shown in Figure 2 so that the spring n forces the collar along the hammer shaft and removes

the swivel pin or projection *m* so that the shoulder *k* on the hammer arm will be out of its path and in consequence rotation of the swivel by the bunter on the sley will not 5 actuate the transferrer.

The parts may be adapted to be subsequently properly positioned by hand or suitable automatic means may be provided for the purpose.

10 It is to be understood that the foregoing details of construction are given by way of illustration and not of limitation since I may vary the form of transferrer hammer and the means adopted for actuating the 15 weft replenishing depending upon the class of work which the loom may be called upon to execute or any practical requirements that may have to be fulfilled.

Having now described my invention, what 20 I claim as new and desire to secure by Letters Patent is:—

1. In automatic weft replenishing mechanism for looms of the kind comprising a cop transferrer operated by a swivel actuated by the sley when the weft is to be replenished, the combination of a cop transferrer, a swivel mounted co-axially with said transferrer and adapted to be rotated by the action of the sley in coming in contact therewith, a movable member carried by said swivel and normally adapted to be positioned for rotating the transferrer when the swivel is rotated by the sley and means adapted to move said member so that the 35 transferrer will be out of its path in the event of the shuttle not being properly positioned in the shuttle box.

2. Automatic weft replenishing mechanism for looms of the kind referred to comprising in combination a transferrer, a swivel for actuating said transferrer, a movable pin carried by said swivel and normally adapted to engage a projection upon the transferrer for operating the same when the swivel is rotated and means adapted 45 to move said pin so that the transferrer will be out of its path in the event of the shuttle not being properly positioned in the shuttle box.

3. Automatic weft replenishing mechanism for looms of the kind referred to comprising in combination a transferrer, a swivel for actuating said transferrer, a mov-

able pin carried by the swivel so that normally it will engage a projection on the 55 transfferer when the swivel is rotated, spring means for moving the pin so that it will not engage with the transfferer, means normally restraining said spring means from operation and means releasing 60 said spring restraining means in the event of the shuttle not being properly positioned in the shuttle box.

4. Automatic weft replenishing mechanism for looms of the kind referred to comprising in combination a transfferer, a swivel mounted co-axially with said transfferer and adapted to be rotated by the sley, a pin movably carried upon said swivel and adapted normally to engage a projection on the transfferer in order to rotate the latter for replenishing weft and a detector actuated by the shuttle when the same is not properly positioned in the shuttle box to permit movement of said pin so that the 75 latter will not engage with the transfferer.

5. Automatic weft replenishing mechanism for looms of the kind referred to comprising in combination a transfferer, a swivel for actuating said transfferer, a movable pin carried upon said swivel and normally adapted to engage a projection on the transfferer, a spring controlling said pin and a detector actuated by the shuttle when the latter is not properly positioned in the 80 shuttle box to permit the spring to function to remove the pin so that it will not engage the transfferer.

6. Automatic weft replenishing mechanism for looms of the kind referred to comprising in combination a transfferer having a projection thereon, a pin normally adapted to engage said projection, a swivel carrying said pin so that on rotation it will actuate said transfferer, a collar upon 95 said pin, a spring engaging said collar upon one side and a detector engaging said collar upon the other side and movable by the shuttle when the latter is not properly positioned in the shuttle box to disengage from 100 said collar and permit the spring to move said pin so that it shall not engage the transfferer.

In testimony whereof I have signed my name in this specification.

HAROLD EDGAR WHITTAKER.
